(57) **CLAIM**

I claim the ornamental design for a casino chip holder, as shown and described.

DESCRIPTION

FIG. 1 is a front elevational view of the casino chip holder showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front left side perspective view thereof;

FIG. 8 is a cross-sectional view taken along line A-A in FIG. 5; and,

FIG. 9 is a cross-sectional view taken along line B-B in FIG. 5.

The broken lines illustrate portions of the casino chip holder that forms no part of the claimed design. The broken lines in FIGS. 8 and 9 illustrate portions of the interior structure, that form no part of the claimed design.

1 Claim, 6 Drawing Sheets
